Primary Examiner — Llorellys Martinez-Rivera(74) *Attorney, Agent, or Firm* — Gary K. Price(57) **CLAIM**

The ornamental design for a window guard as shown and described.

DESCRIPTION

A portion of the disclosure of this patent document contains material which is subject to copyright protection. The copyright owner has no objections to the facsimile reproduction by anyone of the patent document or the patent disclosure, as it appears in the Patent and Trademark Office patent file or records, but otherwise reserves all copyright rights whatsoever.

FIG. 1 is a top perspective view of a window guard, showing my new design in a state of use.

FIG. 2 is an end view of the window guard in FIG. 1.

FIG. 3 is another end view of the window guard in FIG. 1.

FIG. 4 is a bottom perspective view of the window guard in FIG. 1; and,

FIG. 5 is another bottom perspective view of the window guard in FIG. 1.

The broken lines shown in FIG. 1 represent environmental subject matter only and form no part of the claimed design.

1 Claim, 5 Drawing Sheets(56)
